F. A. SEIFERT & E. D. NELLIS.
HEATING STOVE.

No. 18,737.

Patented Nov. 13, 1888.

UNITED STATES PATENT OFFICE.

FRANK A. SEIFFERT AND EMERY D. NELLIS, OF ST. LOUIS, MISSOURI,
ASSIGNORS TO THE BRIDGE AND BEACH MANUFACTURING COMPANY,
OF SAME PLACE.

DESIGN FOR A HEATING-STOVE.

SPECIFICATION forming part of Design No. 18,737, dated November 13, 1888.

Application filed September 13, 1888. Serial No. 285,344. Term of patent 14 years.

To all whom it may concern:

Be it known that we, FRANK A. SEIFFERT and EMERY D. NELLIS, of St. Louis, Missouri, have jointly invented and produced a new and original Design for Heating-Stoves, of which the following is a full, clear, and exact description, reference being had to the accompanying engraving, forming part thereof, in which the newly-designed stove is shown in perspective.

10 The present design consists partly in the general configuration of the stove and partly in the ornamentation appearing thereon.

The stove-body A is an upright rectangular prism supported upon a base, B, which extends in front of the body, forming a hearth, b, and is sustained by the legs CCCC. A foot-rest, D, is attached to the stove above the hearth. The top E of stove slightly overhangs the body and is slightly crowned, and the structure at its top usually terminates in an urn or figure, F, upon a rounded base, f, resting in turn upon the stove-top E, all substantially as shown.

Upon the legs C appear flutings c, terminating at the upper end in scrolls c' c', as shown. 25 The hearth and base B are smooth. Scroll and leaf work a appears upon the lower central part of the front of the body A. Flutings a' are shown at the side edges of the body-front, and 30 the body-front, by means of vertical and horizontal lines a'', presents a paneled appearance. The leading characteristic, however, of the body-front is an ornamentation, a', of a moresque character. The ends a' of the stove- 35 body are also ornamented with work a'' of a

similar character. A dog-tooth ornamentation, e, is shown beneath the eaves of the top E. The edge e' of the top is smooth; but the principal portion of the top, including the figure-base f, has an ornamentation, e'', of a 40 moresque nature.

We claim—

1. The design for a heating-stove herein shown and described, the same consisting of the rectangular prismatic body resting upon 45 the base and legs and having the overhanging top, said legs bearing the ornamentation representing the flutings terminating in a scroll, said body having the superimposed ornamentation representing the scroll and leaf work a, 50 the flutings a', and the moresque work, and said top at its eaves having the dog-tooth ornamentation and upon its upper side the moresque work e'.

2. In a design for a heating-stove herein shown and described, the top, the same consisting of the crown or top surmounted by the figure F upon a rounded base.

3. In a design for a heating-stove herein shown and described, the body, the same consisting of the upright rectangular prismatic body bearing upon its front the ornamentation representing the scroll and leaf work and the moresque work, arranged as described.

Witness our hands this 22d day of June, 1888.

FRANK A. SEIFFERT.
EMERY D. NELLIS.
